UNITED STATES PATENT OFFICE

162,996

SLICING MACHINE

Peter M. Sivertsen, Greenwich, Conn.

Application April 13, 1950, Serial No. 9,178

Term of patent 14 years

(Cl. D55—1)

To all whom it may concern:

Be it known that I, Peter M. Sivertsen, a citizen of the United States, residing at Greenwich, in the county of Fairfield and State of Connecticut, have invented a new, original, and ornamental Design for Slicing Machine, of which the following is a specification, reference being had to the accompanying drawing, forming a part hereof.

Fig. 1 is a front perspective looking down at the front right hand corner of a slicing machine embodying my new design.

Fig. 2 is a rear perspective looking down at the rear right hand corner.

Fig. 3 is a rear perspective looking down at the rear left hand corner.

Fig. 4 is a front perspective looking down at the front left hand corner.

I claim:

The ornamental design for a slicing machine, as shown.

PETER M. SIVERTSEN.
